(**) Term: **14 Years**

CLAIM

(21) Appl. No.: **29/180,242**

The ornamental design for a surface configuration of a rear bumper for a vehicle, as shown and described.

(22) Filed: **Apr. 22, 2003**

DESCRIPTION

(30) Foreign Application Priority Data

This application is related to co-pending Application Serial No. 29/180,269, of the inventor, entitled “Surface Configuration of a Vehicle, Toy and/or Other Replicas”.

Oct. 23, 2002 (DE) 402 08 872
(51) LOC (7) Cl. **12-16**
(52) U.S. Cl. **D12/169**
(58) Field of Search D12/169, 196,
D12/90-92; 296/180.1, 180.2; 293/113,
115, 117, 120

FIG. 1 is a perspective view of a surface configuration of a rear bumper for a vehicle according to my novel design; FIG. 2 is a left side view of the surface configuration of a rear bumper for a vehicle according to my novel design; FIG. 3 is a right side view of the surface configuration of a rear bumper for a vehicle according to my novel design; and, FIG. 4 is a front view of the surface configuration of a rear bumper for a vehicle according to my novel design. The broken lines are for illustrative purposes only and form no part of the claimed design.
